TYPEWRITING MACHINE

Jesse A. B. Smith, Stamford, Conn., assignor to
 Underwood Elliott Fisher Company, New York,
 N. Y., a corporation of Delaware

Application September 14, 1937, Serial No. 163,738

21 Claims. (Cl. 197—84)

This invention relates to typewriting machines and more particularly to line-justifying means therefor.

It is an object of this invention to provide a simple, inexpensive and reliably operative justifying-device for typewriting machines which may be quickly and easily regulated to the desired setting. Other objects will be apparent as the description of the invention proceeds.

10 The invention as shown in the accompanying drawings and as hereinafter described comprises means by which the work-sheet is adapted to be advanced during retyping of a line coactively with the actuation of a spacer-mechanism or 15 independently thereof so that each line of type is modified or lengthened, preferably by distance increase at the word-spaces of the line, whereby each line will terminate at a uniform column-line to define an even marginal area on the work-sheet, thus simulating the appearance of a printed page. Work-sheet-holding means are provided which include endwise movable members or sprockets for maintaining alignment of the work-sheet by positively engaging portions of 20 same and means are provided, in association with the mentioned members, by which the work-sheet may be moved to the left in word-spacing to thus increase the normal space occasioned by the manipulation of the carriage escapement. To enable the operator to quickly and accurately determine the line-length deficiency of any line in the original copy, such copy is made on a special form sheet, as will 25 hereinafter appear.

30 A feature of the invention is that it permits optional use of the justifying means at the will of the operator, so that a typewriting machine thus equipped, may be used to produce typing of the usual kind when rapid work is required, or may instantly employ the justifying-device when work of a particular character is desired. The typewriting machine of the invention affords other advantages in operation by providing means for the joint operation of the usual 35 spacer-mechanism with the justifying-device at the option of the operator, so that, as the machine is operated by the conventional space-bar to produce a letter-space, such space is automatically expanded a predetermined amount to effect the required extension of the typed line in justifying same.

40 A further feature of the invention in its present embodiments resides in its easy adaptability to standard machines, the changes necessary for 45 such adaptation being confined substantially to

the platen-carriage and immediately related parts.

The process of producing a justified type-sheet may include retyping from a copy sheet having a series of parallel lines disposed in a vertical column embracing the field of normally found line-ends, which column-lines are predeterminedly related to the setting means for the shiftable sheet-holder. By means of such copy sheet the operator may instantly determine the 10 number of letter-spaces by which a typed line should be elongated to terminate at a particular margin. In retyping for justifying, the operator may quickly set the mechanism of the present invention for any line by adjusting an indicator 15 in accordance with a reading from the copy sheet, which in turn, sets a regulator of the feed or shift-mechanism for the sheet-holder so that a predetermined amount of feed or shift may be caused to cumulate with each letter-space between words in any given line.

Other features and advantages will herein-after appear.

In the accompanying drawings,

Figure 1 is a perspective view of one embodiment of the invention, certain of the parts being broken away, illustrating the work-holder and carriage organization and associated justifying-mechanism at initial position.

Figure 2 is a sectional view through the typewriting machine, embodying the justifying-mechanism shown in Figure 1, taken on the front and back plane just outside the work-holder shifting-mechanism.

Figure 3 is a view similar to Figure 2 but showing the work-holder shifting-mechanism in modified form.

Figure 4 is an enlarged front elevation of the work-holder and carriage organization at the completion of justifying a type-line and showing a work-sheet in position, portions of the apparatus being shown in section.

Figure 5 is a fragmentary perspective view similar to Figure 1, but showing the justifying-mechanism in position as may occur at an intermediate stage of retyping a line in justifying.

Figure 6 is a fragmentary sectional view taken on the plane 6—6 of Figure 4 and illustrating the operation of releasing the work-holder shift-restoring spring.

Figure 7 is a detailed plan view of the indicator scale and associated feed-regulating lever.

Figure 8 is an elevation of the preliminary work-sheet, including spacing indicia and typed

55

in the usual typing, preparatory to retying for line-justifying, and

Figure 9 is an elevation of the finish work-sheet, the type-lines being similar to that shown in Figure 8, but retyped for line justifying.

In the physical embodiment of the invention illustrated in the drawings, the line-justifying mechanism is incorporated in the standard Underwood typewriter machine. A carriage 10 is mounted on a typewriter frame 11 for lateral letter-feed movement relative thereto, the carriage being guided on a rod 12 at the rear portion and a channel-track 13 at the forward portion. The carriage 10 is urged to shift to the left in the usual manner as by a spring bank 14, this movement being controlled by a letter-feed escapement-mechanism 15, Figure 2.

The carriage 10 carries a gear-rack 16 in mesh with a pinion 17 having an escapement-wheel 18 rotatable therewith in one direction by a spring-pressed pawl 17¹, Figure 4, the latter permitting return of the carriage independently of the escapement-mechanism 15. A rockable member 19 may oscillate about a pivot 20 to move a stop-dog 21 and a pawl 22 on the member 19 alternately into engagement with the teeth of the escapement-wheel 18 to permit intermittent letter-feed movement of the carriage 10 in the well-known manner. As is usual in the standard Underwood machine, the letter-feed or carriage-feed escapement 15 may be actuated either by type-bars 23 engaging a universal bar, not shown, as for letter-spacing during typing, or by a space-bar or key 24, as in word-spacing. The mentioned universal bar, not shown, is operably connected to a slide-plate 25 having arms 26 extending therefrom, flexibly joined at 27 to crank-arms 28 affixed to a shaft 29, the slide-plate 25 during type-bar swinging, engaging the rockable member 19 to actuate the escapement-mechanism 15. In word-spacing, the space-bar 24 carried on a spacer-lever 30, is depressed so that lever 30 actuates a forked arm 31 secured to the shaft 29 to move the slide-plate 25 by the crank-arms 28 into engagement with the rockable member 19. The forked arm 31 may be operably connected to a ribbon-feed device, not shown.

The apparatus thus far described, embodies the usual letter-feed and word-spacing mechanism which, during typing, operates to advance the carriage intermittently at a constantly uniform distance for each letter-feed or word-space, thereby producing a typed sheet on which the individual lines terminate at varying distances from the right-hand margin, thus defining a jagged edge. The invention provides novel mechanism cooperating between the carriage and work-sheet holding means by which each line of type is extended to a uniform margin, preferably by expanding each word-space a predetermined increment, so that each line will terminate evenly at a desired column-line. The invention is carried out by providing means for intermittently advancing work-sheet holding means relative to the carriage, including feed-mechanism operative by a justifying space-bar, preferably at each word-space and operable at a predetermined adjustable rate. The rate of advancement may be varied in accordance with the number of letter-spaces by which a given typed line is to be lengthened and the number of word-spaces in such line so as to distribute the length-increase evenly over the entire line. The work-sheet holding means is thus normally letter-fed uniformly rela-

tively to the printing elements or type-bars 23, but is also adapted to be moved relatively to both the printing elements and the platen for effecting a change in the line length.

A shaft 35 is journaled against axial movement in the carriage 10, being manually rotated as by a knob 36 or line-space lever 37 provided for intermittent uniform rotation of the shaft 35 in line-spacing, the lever 37 being pivoted at 38 to engage a plunger 39 operably associated by a pawl 40, Figure 4, to rotate a ratchet-wheel 41 on the shaft 35. The shaft 35 carries a platen 43 having end-plates 44 affixed as by set screws 45 thereto. A pair of sprockets 46, 47, constituting a pin-type line-space feeding device and embodying the mentioned means for holding a work-sheet against lateral displacement and, or misalignment, are disposed in axial alignment at each end of the platen 43, the respective sprockets being amply spaced to permit adequate movement to or from the platen 43 during line-justifying. The sprockets 46, 47 are connected by a series of tie-rods 48 which pass through the platen 43, making sliding connection with the end-plates 44 thereof. The tie-rods 48 cause the respective sprockets 46, 47 to move axially in unison independently of the platen 43 and assure axial alignment of the sprockets and platen, as well as rotation of these elements in unison, as in line-spacing of the work-sheet.

The shaft 35 carries a sleeve 50 rotatably free thereon and secured against endwise movement by suitable means. The sleeve 50 has formed on its periphery a thread 51 on which is fitted a threaded collar 52. The collar 52 is associated with the sprockets 46, 47, preferably with the left sprocket 46, in such manner as to impart axial movement to the sprockets although being free to rotate independently thereof. The collar 52 has series of rollers 53 rotatably mounted by studs 54 thereon and abutting the sprocket 46 on each side by which the collar and sprocket move axially in unison.

As shown more clearly in Figure 4, the sprockets 46, 47 are each provided with a series of teeth 55 or other suitable means to prevent lateral shifting of a work-sheet 56 thereon, the latter having series of perforations 57 at marginal portions into which the teeth 55 engage. A rest-plate 58 is mounted on the carriage 10, being inclined at the rear of the platen, and extends partly around same to facilitate placement of a work-sheet into the machine and hold same onto the sprockets. It is preferred that the sprockets 46, 47 substantially support the work-sheet 56, the platen 43 being of such diameter, relative to the sprockets, as to permit lateral sliding of the work-sheet thereon, although affording adequate backing for same across the typing area.

The collar 52 is prevented from rotating with the sleeve 50 by a keeper-arm 60 fixed to a rod 61 of the carriage 10, the keeper-arm 60 having a tongue 62 slidably disposed in a groove 63 of the collar 52. The rod 61 also serves to anchor a restoring spring 64 at one end which has a series of turns around the sleeve 50 and fixed thereto at its inner end. The restoring spring 64 is progressively tensioned or wound up as the sleeve 50 rotates during line-justifying, so that upon completion of a typed line, by operation of a suitable release, the spring 64 will reversely rotate the sleeve 50 to restore the collar 52 and associated sprockets 46, 47 to initial position preliminary to typing the succeeding line. The sleeve 50 car-

ries pins 65 or other suitable abutments to limit endwise movement of the collar 52 thereon, the latter having shoulders 66 against which the respective pins 65 may engage during rotation of sleeve 50. Springs 59 press between the platen 43 and sprocket 41 so as to take up any backlash in the fit of collar 52 on the threads 51.

From the foregoing it will be seen, that by rotation of the threaded sleeve 50 at desired intervals in typing a line, such as at the word-spaces, the work-sheet supporting sprockets 46, 47 will be caused to shift axially to laterally move the work-sheet 56 so as to vary the spaces in the typed line to adequately lengthen same to terminate at a predetermined margin. The distance from any previous letter-feeding step position may be altered at will. The means for rotating the sleeve 50 at a predeterminable selective degree in line-justifying embodies a feed-mechanism 70 which comprises a ratchet-wheel 71 secured thereto and engageable by a spring-backed pawl 72 carrier on an oscillatory arm 73, the latter being swingable about the shaft 35. Arm 73 is operably joined by a link 74 to a manually-actuated leverage system 75, to be later described, the same terminating in a justifying space-bar or key 67, preferably at the keyboard of the machine adjacent the usual space-bar 24. The stroke of pawl 72 is limited by engaging an abutment 68 which wedges the pawl to press into ratchet-wheel 71 to prevent overthrow of the feed-mechanism 70.

The pawl 72, being reciprocated by movement of the link 74 through the arm 73, has selectively adjustable means by which the effective throw of same may be varied in accordance with certain conditions of the work, to be later defined. Pawl 72 has a pin 76 projecting therefrom to engage the periphery of a cam 77, rotatable about the shaft 35 and having an adjustment or regulator arm 78 extending therefrom by which to adjustably fix the cam 77 to any suitable point in the arc of travel of pawl 72. Adjustment arm 78 carries a resilient detent 79 engageable in one of a series of notches formed in a scale 80 secured to the carriage 10, Figures 1 and 7, the scale bearing certain indicia representing the rate of feed of the feed-mechanism 70. A portion of the cam 77 is arcuately formed concentric with its center of rotation so that the pin 76 traveling thereon, holds the pawl 72 free of the ratchet-wheel 71 for a part of its stroke. The arcuate portion of cam 77 converges into a radially inclined portion 81 from the point 82 down which incline pin 76 travels to allow the pawl 72 to engage a tooth of the ratchet-wheel 71. As afore-indicated, the angular position of cam 77 is adjustable by positioning the arm 78 along the scale 80 so that the point 82 at which the incline begins may be disposed at any point in the arc of travel of the pawl 72, selective on the scale 80 and secured by the detent 79 engaging the notches therein. Thus, the feed-mechanism 70 may be set so that pawl 72 is allowed to engage the ratchet-wheel 71 to rotate same a measured distance equivalent to 1, 2 or more teeth thereof as required although pawl 72 moves a uniform stroke at each operation. During reverse travel of pawl 72, same is lifted from the ratchet by its pin 76 riding up the incline 81 onto the arcuate portion of cam 77.

The ratchet-wheel 71 is prevented from reverse rotation due to the drag of the pawl 72 on return stroke by a spring-urged lock-pawl 84, Figure 5, carried on a release-lever 85 pivoted

at 86 on the carriage 10 and having a release-key 87 at its end. Release-lever 85 bears a cam 88 engageable by a pin 89 of the line-space plunger 39, whereby the lock-pawl 84 may be released from the ratchet-wheel 71, Figure 6, 5 coaxively with operation of the line-space lever 37, to effect the restoring of the justifying-mechanism to initial position at the completion of each type-line, or the justifying-mechanism may be independently released by pressing release-key 10 87. In either instance, the screw-sleeve 50 is restored to initial setting by the wound spring 64, at which position collar 52 abuts a pin 65.

As aforeindicated, the pawl 72 is actuated through the link 74 which is operated by depressing the justifying space-bar 67 through the leverage-system 75, the link being flexibly joined to a rockable frame 90. The carriage 10 moves axially during typing, and, consequently, the leverage system 75, being laterally stationary, 20 makes a sliding connection with the carriage 10. The rockable frame 90 presents an elongate rigid structure which comprises arms 91 at each end, fulcrumed at 92 on the carriage 10 and fixedly connected at the fulcrum points by a torque-rod 93 and at the free ends of arms 91 by a slide-rod 94, the link 74 being connected to one of the arms 91 at 95. The rockable frame 90 is provided with return-springs 96 anchored on the carriage 10 by which the arm 73 carrying pawl 30 72 is retracted.

The justifying space-bar 67, see Figures 1 and 2, is carried on a justifying lever 97 fulcrumed at 98 on the machine and operatively joined by a pin-and-slot connection 99 to a sub-lever 100 35 fulcrumed at 101, the sub-lever being articulated at 102 to an end of a pull-link 103 having an open slot 104 at its upper end straddling the slide-bar 94 but normally free of same. Although the pull-link 103 functions mainly as a draw-bar, it is desirable that same be operably mounted on the machine so that its upper-end engaging the rockable frame 90, is maintained laterally stationary, the open slot 104 being preferred to facilitate removal of the carriage assembly from the machine. It is also desired that the slot 104 40 therein have a substantially constant relation with the slide-rod 94 without any appreciable backward swinging, to assure smooth action. To function in this manner pull-link 103 has a guide 45 slot 105 which rides on a stud 106 mounted on a fixed member of the machine such as the tubular-frame 107, the guide-slot 105 being so directed with reference to the arc of travel of point 102, that the open slot 104 describes a path coinciding with the swing of slide-rod 94 in its oscillation on the fulcrum 92. Thus, it will be seen that the carriage 10 may be moved across the machine in letter-feed or word-spacing, the slide-rod 94 being substantially free of the slot 104 50 with the leverage-system 75 inactive, although the latter may be actuated at any point in the carriage movement to cause the feed-mechanism 70 to function in line-justifying.

To indicate the progress of the line-justifying 65 process, a dial 108, preferably calibrated in letter-spaces, is provided, the same being mounted on the carriage 10. A pointer 109 is carried on the collar 52 to move laterally therewith along the dial 108. By observing the position of 70 pointer 109 on the dial 108 as the work progresses, the operator may check the functioning of the justifying-mechanism and may additionally actuate same in typing a line to amply modify the line length in justifying.

When it is desired to justify a type-line by expanding same at the letter-spaces the justifying space-bar 67 may be pressed to advance the work-holding means at the same time the space-bar 24 is operated to space a word. In such instance, a releasable lock 110 may be so positioned as to afford joint operation of the space-bar 24 and justifying-bar 67, so that the operator need only depress one of the bars to effect the line-justifying. Lock member 110 may be made, as shown more clearly in Figure 1, to present a swingable link pivoted on the bar 67 to engage the bar 24 for joint operation and being movable free thereof at the will of the operator when independent 15 operation of the justifying-mechanism is desired.

Attention is now directed to Figure 3 representing a modified form of the actuating means for the feed-mechanism 70, same being distinguished from that of the first form by the elimination of the leverage system 75 and the rockable frame 90, other actuating means being provided. This form of the invention embodies feed-mechanism 70 similar to that described for the first form and includes the ratchet-wheel 71 on the screw-sleeve 50, the pawl 72 for actuating the latter through the reciprocatory arm 73, and the cam 77 controlling the effective throw of pawl 76, the position of cam 77 being adjustable by the regulator arm 78 to vary the effective 30 throw of pawl 76. In this modification, the actuating means for the feed-mechanism 70 takes the form of a plunger 111 flexibly joined to the arm 73 at 112 and guided for sliding motion on the carriage 10 in a journal 113. Plunger 111 is manually operated in actuating the feed-mechanism 70 by pressing a button 114 at its forward end against the power of a return-spring 115 until a member of arm 73 engages a stop 116, the button 114 being conveniently accessible to the operator, at the forward part of the machine.

Although line-justifying may be effected by operating the mechanism at random and observing the progress of justifying on dial 108, the procedure preferably followed in justifying the type-lines of a page includes the preparation of a work-sheet 117, Figure 8, typed in the usual manner with uniform word-spaces and even letter-spaces which results in producing a right-hand margin at which the various typed lines define a jagged edge. To assist the operator in determining the actual deficiency of each type-line, that is, the number of letter-spaces of which a certain line is short of the desired margin, the work-sheet on which the preliminary typing is prepared, has previously printed thereon a series of column-lines 118 collectively defining a vertical border or field within which the usually typed uneven lines terminate. The respective column-lines are separated a distance equal to the usual letter-spacing produced by the machine and are numbered from right to left, the zero line representing that at which each type-line is to terminate in the finished, justified sheet.

The invention functions to extend or elongate a type-line preferably by expanding each word-space in the line a uniform predetermined degree in order that the type-line terminate at the zero-column line 118. For exact work two variants or factors are to be considered in setting the justifying-mechanism, namely, the shortage of 65 each line expressed in letter-spaces, and the number of word-spaces in that line, it being desired to add to each word-space a uniform amount which, in the aggregate, makes up the deficiency of the typed line. For example, it 70 may be assumed that a certain type-line has

eight word-spaces and is three letter-spaces short of the desired margin as exemplified by the upper type-line of Figure 8. It will thus be required to expand each of the eight word-spaces in retyping, by an amount equivalent to three-eighths of a letter-space so that the aggregate line will be amply lengthened to terminate at the zero-margin line. The two mentioned variants form the fraction $\frac{3}{8}$, the decimal equivalent being .375, to which figure the regulator 10 arm 78 is set on the scale 80, Figure 7, the notch opposite numeral 4 on the dial being suitable for such a decimal. Any degree of advancement for the work-sheet in line-justifying may be similarly determined on the basis of word-spaces in a given 15 line and the shortage of the line to the desired margin.

On work of the average kind, such as letter-writing, it has been found that each type-line contains a substantially uniform number of 20 word-spaces, varying only one or two word-spaces from the average. Because of this uniformity in the number of word-spaces, this factor need not be considered in setting the feed-mechanism for most work, it being necessary to 25 consider only the number of letter-spaces required to extend the type-line. In other words, the regulator arm at the scale 80 may be set at the actual number of letter-spaces by which the type-line is to be extended.

It will thus be apparent that as the typing of a line progresses each word-space is expanded by the automatic shifting of the work-sheet carried on the sprockets 46, 47, the advancement being effected by axially moving the sprockets 46, 47 35 from right to left, actuated by rotation of the screw 50 in the collar 52 through the feed-mechanism 70, the latter being set to feed the predetermined amount in accordance with the number of word-spaces and the length deficiency of each 40 line. Although it is desired to set the feed-mechanism to operate in accordance with the predetermined requirements, the operator may justify a line by actuating the feed-mechanism 70 at such intervals in the type-line as her judgment 45 dictates, for which purpose the scale 108 and pointer 109 may be of substantial assistance by affording means by which the amount of type-line expansion may be constantly observed. A purpose of scale 108 is exemplified in Figure 5 50 wherein the feed-mechanism is shown in position at which the work-sheet has been advanced to the left, a distance equivalent to three letter-spaces, as would be required to justify the top type-line of the preliminary work-sheet, Figure 8.

The use of a preliminary sheet 117 of perforated form to assure accurate lateral positioning on the sprockets 46, 47, is of advantage in so aligning the border-lines 118 as to accurately register same with the fixed printing-point of the machine as the end of a type-line is typed, so 60 that some of the letters of the last word in the type-line are impressed exactly on the line to make it easy to determine exactly the number of spaces by which the line is deficient. In reference to the typing of the finished sheet, Figure 65 9, the use of a perforated sheet herein is of further advantage by positively and accurately registering the work-sheet with the predetermined left-hand margin-line so that the operator may be assured that each line, after justifying, will 70 terminate at an exact right-hand margin-line and, of course, in an even border. In each case, the work-holding means embodied in the sprockets 46, 47 serves to positively allocate both the preliminary work-sheet and the finish work- 75

sheet in an identical lateral position in the machine.

Variations may be resorted to within the scope of the invention, and portions of the improvements may be used without others.

Having thus described my invention, I claim:

1. In a line-justifying mechanism for type-writing machines, in combination, a main frame, a carriage shiftable in line typing relative thereto, spacer-mechanism for moving said carriage at uniform steps, means for normally holding a work-sheet against lateral displacement upon the carriage, means for shifting said holding means in lateral direction relative to said carriage selectively variable, measured distances, whereby the intermittent movement of said holding means relative to said main frame as imparted to the carriage by the spacer mechanism may be modified, to modify the length of a type-line to justify the same, and separable connecting means between said carriage-spacer mechanism and said means for shifting said holding means for effecting joint operation of said mechanism at the will of the operator.

2. In a justifying-mechanism for typewriting

25 2. In a justifying-mechanism for typewriting machines, in combination, a main frame, a carriage movable in line typing relative thereto, spacer-mechanism for moving said carriage at uniform steps, a platen endwise stationary on said carriage, a pair of sprockets rotatable on said carriage, the teeth of which may engage perforations in a work-sheet for laterally shifting same independently of said platen, and means for laterally shifting said sprockets relative to said carriage and platen selectively variable measured distances, whereby the movement of the work-sheet relative to said main frame is varied, so as to modify the length of a type-line to justify same, said sprockets and said platen being in axial alignment and rotatable in unison for line spacing of a work-sheet.

3. In a typewriting machine, the combination with a main frame, a carriage movable relative to said main frame in line typing, spacer-mechanism for moving said carriage at uniform steps, and means for actuating said spacer-mechanism including a spacer-key at the front of the machine, of a line-justifying mechanism, comprising work-sheet holding means shiftable on said carriage, means for shifting said holding means relative to said carriage selectively variable measured distances, whereby the intermittent movement of said holding means relative to said main frame is varied so as to modify the length of a typed line to a predetermined degree in justifying same, said work-holder shifting means including a justifying-key adjacent said spacer-key, and a lock for connecting at will the justifying-key and spacer-key for operating the justifying-mechanism simultaneously with the spacing operation.

4. In a line-justifying mechanism for type-writing machines, in combination, a main frame, a carriage shiftable in line typing relative thereto, spacer-mechanism for moving said carriage laterally at uniform steps, means for holding a work-sheet against lateral displacement, means for shifting said holding means relative to said carriage in selectively variable measured dis-

70 tances, said means comprising a screw rotatably mounted on said carriage, a collar threadedly engaging said screw and operably connected to said work-sheet holding means, and a pawl and ratchet drive associated with said screw, the effective throw of said pawl being selectively vari-
75

able to rotate said screw a predetermined degree whereby to vary the movement of said work-sheet holding means relative to said main frame, so as to modify the length of a type-line to justify same.

5. In a line-justifying mechanism for type-writing machines, in combination, a main frame, a carriage shiftable in line typing relative thereto, spacer-mechanism for moving said carriage at uniform steps, means for holding a work-sheet against lateral displacement, means for shifting said holding means laterally relative to said carriage in selectively variable measured distances, said means comprising a screw rotatably mounted on said carriage, a collar threadedly engaging said screw and operably connected to said work-sheet holding means, a pawl and ratchet drive associated with said screw, the effective throw of said pawl being selectively variable to rotate said screw a predetermined degree, and means for actuating said pawl including a leverage train mounted on the main frame, and a rockable frame pivoted on said carriage and having a sliding connection with said leverage train to permit free shifting of the carriage in line typing. 10 15 20 25

6. In a line-justifying mechanism for type-writing machines, in combination, a main frame, a carriage shiftable in line typing relative thereto, spacer-mechanism for moving said carriage at uniform steps, means for holding a work-sheet against lateral displacement, means laterally for shifting said holding means relative to said carriage in selectively variable measured distances, said means comprising a screw rotatably mounted on said carriage, a collar threadedly engaging said screw and operably connected to said work-sheet holding means, a pawl and ratchet drive associated with said screw, the effective throw of said pawl being selectively variable to rotate said screw a predetermined degree, and means for actuating said pawl including a rockable frame pivoted on said carriage and a leverage train mounted on the main frame and including an actuating lever having a pin-and-slot connection with said rockable frame, said link having guide means whereby the connection thereof moves in accord with the swing of said rockable frame. 30 35 40 45

7. In a line-justifying mechanism for type-writing machines, in combination, a main frame, 50 a carriage shiftable in line typing relative thereto, spacer-mechanism for moving said carriage at uniform steps, means for holding a work-sheet against lateral displacement, means for laterally shifting said holding means relative to said carriage in selectively variable measured distances, 55 said means comprising a screw rotatably mounted on said carriage, a collar threadedly engaging said screw and operably connected to said work-sheet holding means, a pawl and ratchet drive 60 associated with said screw, and an adjustable cam in the path of travel of said pawl, said cam being engageable by said pawl to control the degree of stroke of same effective on said ratchet, 65 whereby to vary the intermittent movement of 70 said work-sheet holding means relative to the main frame, so as to modify the length of a type-line to justify same.

8. In a line-justifying mechanism for typewriting machines, in combination, a main frame, a carriage shiftable in line typing relative thereto, a pacer-mechanism for moving said carriage at uniform steps, means for holding a work-sheet against lateral displacement, and means for laterally shafting said holding means relative to 75

said carriage in selectively variable measured distances, said means comprising a screw rotatably mounted on said carriage, a collar threadedly engaging said screw and operably connected 5 to said work-sheet holding means, and selectively variable actuating means for rotating said screw a predetermined degree, whereby to vary the intermittent movement of said holding means relative to said main frame, effective in modifying 10 the length of a type-line to justify same, said screw having a restoring spring associated therewith to be further tensioned during advancement of said collar and adapted to reversely rotate said screw to return said collar and the 15 work-sheet holding means therewith, to initial position.

9. In a line-justifying mechanism for typewriting machines, in combination, a main frame, a carriage shiftable in line typing relative thereto, spacer-mechanism for moving said carriage at uniform steps, means for holding a work-sheet against lateral displacement, means for shifting said holding means relative to said carriage in selectively variable measured distances, 20 said means comprising a screw rotatably mounted on said carriage, a collar threadedly engaging said screw and operably connected to said work-sheet holding means, a pawl and ratchet drive associated with said screw, and an 25 adjustable cam to control the amount of effective throw of said pawl upon the ratchet when said ratchet-drive is operated, whereby the intermittent movement of said work-sheet holding means relative to the main frame may be varied, so 30 as to modify the length of a type-line to justify same, said settable cam including an adjustment arm registerable with an indicator dial representing the rates of feed of said pawl and ratchet device.

40 10. In a justifying-mechanism for typewriting machines, in combination, a main frame, a carriage movable in line typing relative thereto, spacer-mechanism for moving said carriage at uniform steps, a platen endwise stationary on 45 said carriage, a pair of sprockets rotatable on said carriage, the teeth of which may engage perforations in a work-sheet for laterally shifting same independently of said platen, means for laterally shifting said sprockets relative to said carriage and platen to modify the length of a type-line to justify same, and a series of rods 50 slidable longitudinally in the platen to fixedly interconnect said sprockets for rotation in unison with the said platen.

55 11. In a justifying-mechanism for typewriting machines, in combination, a main frame, a carriage movable in line typing relative thereto, spacer-mechanism for moving said carriage at uniform steps, a platen endwise stationary on 60 said carriage, a pair of sprockets rotatable on said carriage, the teeth of which may engage the marginal perforations in a work-sheet for laterally shifting same independently of said platen, means for variably shifting said sprockets 65 relative to said carriage and platen comprising a feed screw rotatably mounted on said carriage and operably connected with said sprockets for laterally shifting the same, a pawl and ratchet drive associated with said screw, a spring-backed 70 pawl associated with said ratchet to normally prevent reverse movement thereof, line-space mechanism operable to intermittently rotate said sprockets to line space a work-sheet and means for releasing said pawl by the operation of said 75 line-space mechanism.

12. In a justifying-mechanism for typewriting machines, in combination, a main frame, a carriage movable in line typing relative thereto, carriage-feed-mechanism for moving said carriage at uniform steps, a platen normally endwise stationary on said carriage, a pair of sprockets rotatable on said carriage, the teeth of which may engage the marginal perforations in a work-sheet, means for laterally shifting said sprockets relative to said carriage and platen in selectively variable fractions of the uniform 5 steps of carriage movement, said means comprising a feed screw rotatably mounted on said carriage and operably connected with said sprockets for laterally shifting the same, a spring returned 10 pawl and ratchet drive associated with said screw, the effective throw of said pawl being selectively variable to rotate said screw a predetermined degree, a line-spacer mechanism for intermittently rotating said sprockets to advance the 15 work-sheet in line-space movement, including a reciprocator member, a spring-backed check pawl associated with said ratchet to prevent reverse movement thereof, and an abutting connection between said plunger and check pawl 20 whereby said check pawl may be released coactively with the operation of said line-spacer mechanism to permit restoration of said ratchet drive under the power of its spring.

13. In a typewriting machine having a letter- 30 feeding carriage and types movable to a common printing point, a justifying device comprising a platen on said carriage, means for holding a work sheet against said platen, and means for shifting said holding means relative to said platen in the 35 line of feed a measured distance, and a settable shift-regulator associated with said shifting means whereby the distance between the previous letter-feeding step position of the sheet and the printing point can be varied by the operation of said 40 shifting means to regulated extents.

14. In a typewriting machine, a letter-feeding carriage, a platen mounted thereon, sprockets revolvably mounted in the carriage, said sprockets cooperating with a perforated work-sheet to 45 hold the same, said sprockets, when rotated, adapted to line-space said work-sheet, and means to laterally displace said sprockets simultaneously on the said carriage a measured distance, and a regulator associated with said sprocket-displacing means whereby the lateral position of said 50 work-sheet can be changed within the said carriage to regulated extents.

15. In a typewriting machine, the combination with a main frame, a carriage movable relative 55 to said main frame in line typing and carriage feed-mechanism for moving said carriage at uniform steps, of line-justifying mechanism comprising, work-sheet holding means engaging a work sheet against lateral displacement, a platen 60 for backing the work-sheet across its typing area and laterally immovable on said carriage, means which, when actuated, causes a measured lateral movement of the work-sheet holding means upon the said carriage, and means for predeterminate- 65 ly regulating the said measured lateral movement of said work-sheet holding means.

16. In a typewriter, a frame, a letter feeding carriage, a platen fixed against lateral movement with respect to the carriage, typing elements selectively movable against the platen, a device for holding a work-sheet in operative relation to the platen, said device being movable to effect displacement of the work-sheet on the platen in the direction of letter-feed movement thereof, 75

- mechanism actuatable to line-space said work-sheet, means to variably move said work-sheet holding device small variable distances to obtain variable movements of the work-sheet with 5 respect to the frame in addition to regular letter-feeding movement of the carriage to thus provide for line-justification, and means supported on the carriage and operative under control of said line-space mechanism upon actuation 10 thereof for returning said work-sheet holding device to a normal position upon the carriage.
17. In a typewriting machine, a frame, a carriage, means to letter-feed said carriage, a platen fixed against lateral movement with respect to 15 the carriage, typing elements selectively movable against the platen, means for holding a work-sheet in operative relation to the platen, said means being movable to effect displacement of the work-sheet on the platen in the direction of 20 letter-feed movement thereof, means operable to impart, with respect to the carriage, variable movement to said work-sheet holding means in the line of carriage-feed, said last said means including a device to regulate the magnitude of 25 said imitable movements, whereby variable work-sheet movements can be obtained with respect to the frame in addition to regular letter-feeding movement of the carriage, to thus provide for line-justification, a key operating said 30 letter-feed means, and means to connect said key to the means to impart movement to the work-sheet holding means.
18. In a typewriter, a platen for backing a work-sheet, means to support the said platen, 35 a keyboard, type-keys in the keyboard, character typing elements operable by said type-keys, common supporting means for said typing elements, said elements being movable against the said platen to a common printing point, a work-sheet holder upon the said platen-supporting means movably holding said work-sheet against the platen in the line of feed, means operable to relatively letter-feed one of said supporting means upon the other, means for imparting to said work-sheet holder, with respect to the platen and platen supporting means, variable movements in the line of relative feed of the said supporting means, said last said means including a regulating device for predeterminedly varying the magnitude of said movements, to thereby obtain variable movements between the work-sheet and the said typing elements in addition to regular letter-feeding movement between the said supporting means, a key operating said letter-feed means, and means to connect said key to the means to impart movement to the work-sheet holding means.
19. In a typewriting machine, a frame, a letter-feeding carriage, a platen fixed upon the carriage to letter-feed therewith, typing elements 5 selectively movable against said platen, a pin-type work-sheet holder for movably holding a work-sheet against the platen upon the carriage in the line of carriage-feed and also transverse to the line of carriage-feed, means to line-space said pin-type work-sheet holder transverse to the line of carriage-feed, and means operable to impart, with respect to the carriage and said platen, variable movements to the pin-type work-sheet holder in the line of carriage-feed, said last said means including a device to regulate the magnitude of said imitable movements, whereby variable movements of the work-sheet can be obtained with respect to the frame in addition to the regular letter-feeding movements of the carriage to thus provide for line-justification. 10
20. In a typewriting machine, the combination with a frame, a letter-feeding carriage, a platen laterally fixed on the carriage, typing elements selectively movable against said platen, of carriage-feeding means, a work-sheet holder supported on the carriage and adapted to support a work-sheet against said platen and movable in the line of feed on the carriage, screw-feed means operable to impart with respect to the carriage and said platen, variable movements to said work-sheet holder in the line of carriage-feed, said screw-feed means including a device on the carriage to regulate the magnitude of said imitable movements, whereby variable movements of the work-sheet can be obtained with respect to the frame in addition to regular letter-feeding movement of the carriage to thus provide for line-justification, and an operating member connected to said carriage-feeding 30 means, and means to connect said member to said screw-feed means to conjointly operate said carriage-feeding means and said screw-feed means. 35
21. In a typewriting machine, the combination with a frame, a letter-feeding carriage, a platen laterally fixed on the carriage, typing elements, a keyboard, and keys in the keyboard operable to move said types selectively against said platen, of carriage-feeding means, a work-sheet holder supported on the carriage and adapted to support a work-sheet against the platen and movable in the line of feed on the carriage, means for moving said work holder with respect to the carriage and the platen, small variable distances 40 to obtain variable movements of the work-sheet holder with respect to the frame in addition to the movements derived from the regular letter-feeding movement of the carriage, to thus provide for line justification, a key operating said carriage-feeding means, and means to connect said key to the means to impart movement to the work-sheet holding means. 45
